UNITED STATES PATENT OFFICE.

JOSEPH J. LYNN, OF MOOSE JAW, SASKATCHEWAN, CANADA.

DOOR-CATCH.

1,311,982.

Specification of Letters Patent.

Patented Aug. 5, 1919.

Application filed May 28, 1917, Serial No. 171,536. Renewed May 23, 1919. Serial No. 299,382.

To all whom it may concern:

Be it known that I, JOSEPH J. LYNN, a subject of the King of Great Britain, and a resident of Moose Jaw, in the Province 5 of Saskatchewan and Dominion of Canada, have invented certain new and useful Improvements in Door-Catches, of which the following is a specification.

The present invention relates to door 10 catches, and more particularly to a catch for application to light doors, such as screen doors and the like.

An object of the present invention is to provide a small, economically constructed 15 catch which is strong and durable, which can not easily be distorted and bent out of alinement, and which may be sold at a relatively low cost.

The invention further aims at the provision 20 of a door catch of this character which may be constructed from sheet metal and wire, and which may be readily applied to the door and the door casing without mutilating the same.

The above, and various other objects and 25 advantages of this invention will be more or less described, and more or less understood, from the following detailed description of the present preferred embodiment, 30 the same being illustrated in the accompanying drawing, wherein:

Figure 1 is a perspective view of a door 35 catch constructed according to the present invention, and as applied to the door and the casing, the door being shown open.

Fig. 2 is a fragmentary enlarged side elevation of one of the members of the catch.

Fig. 3 is a longitudinal section taken through said member.

Fig. 4 is a horizontal section taken substantially on the line 4—4 of Fig. 3, showing the location of the spring for closing the jaws of the catch.

Fig. 5 is a detail perspective view of 45 the underside of the movable jaw.

Fig. 6 is a detail perspective view, enlarged, of the co-acting member adapted to be carried upon the door.

Referring to this drawing, one of the 50 catch members is provided with a casing, the same being preferably formed from a single

sheet of metal which is bent substantially U-shaped to provide a closed side 10, a bottom 11, and a top 12, the bottom and top 11 and 12 being provided with attaching 55 flanges 13 which are turned outwardly from the free edges of the top and bottom and adapted to be secured by screws or the like against the inner side of a door casing A. The casing thus formed is open at its opposite ends, and closed at its inner side by the adjacent face of the door casing A.

The bottom 11 of the casing is provided with a fixed jaw 14 at the forward end thereof, the jaw 14 being preferably in the 65 form of a metallic block which is riveted or otherwise permanently secured to the bottom 11. The jaw 14 is adapted to engage at one side against the side 10 of the casing, and is adapted to coöperate with a movable 70 jaw 15 which is pivoted at its rear end upon a rivet or pin 16 which passes through the side 10 of the casing. The jaw 15 is held against the casing sides 10 and in alinement with the fixed jaw 14 by the pivot pin 16. 75 The jaws 14 and 15 are provided upon their outer ends with oppositely beveled faces 17 forming a flaring throat, and the faces 17 are adapted to converge at their inner ends and to be brought into contact with each other by the closing of the jaws 15 and 14. The jaws 14 and 15 are also provided, 80 near their forward ends, with registering recesses or grooves 18 which extend transversely across the inner opposite faces of 85 the jaws and which provide a pocket, or enclosure for engagement with a co-acting member.

The jaw 15 is yieldingly urged against the fixed jaw 14, by a spring 19 which is interposed between the jaw 15 and the top 12 of the casing, and which is held in position by the provision of a finger 20 which is preferably stamped and bent inwardly from the top 12. The finger 20 is bent into substantially right angles with respect to the top 12. The finger is of reduced width with respect to the top 12, and is adapted to project into the upper end of the spring 19 to hold the latter from displacement.

The co-acting member 21 is in the form 95 of a bail and comprises a single length of

wire which is bent substantially U-shaped and which has its extremities overturned to provide loops 22 and 23 which are preferably elongated to provide slots in the opposite ends of the bail for adjusting the latter. The loops 22 and 23 are turned in opposite directions from the inner ends of the bail 21, and are adapted to lie flat against the inner surface of the lock stile 5 of a door B, and to be held thereagainst by screws or the like. The bail 21 may be adjusted upon the lock stile of the door by loosening the screws and shifting the bail 21 into the desired position. This adjustment is for the purpose of facilitating the mounting of the coöperating members of the catch, and to also admit of the easy readjustment of the catch members when the door settles or sags. It will be noted that 10 the loops 22 and 23 are arranged vertically upon the lock stile so that the bail 21 may be adjusted vertically upon the door. The bail 21 also provides a finger-hold through which the finger may be extended for the 15 purpose of drawing the door into closed position.

When the jaw member is secured to the inside of the door casing A, and the bail 21 is secured to the inner side of the door 20 B, the latter may be drawn into closed position by engaging the bail, and the cross bar of the bail is adapted to enter the throat between the jaws 14 and 15, engage the flaring outer ends 17 of the jaws, and spread 25 the jaws apart by lifting the movable jaw 15 against the tension of the spring 20. As soon as the cross bar of the bail 21 enters the pocket 18, the spring 20 urges the movable jaw into closed position, and the bail 40 21 is yieldingly held between the jaws. It will be noted from Figs. 3 and 5 that the recesses 18 in the jaws are provided with arcuate inner walls and rounded marginal edges so that when sufficient pressure is 45 placed against the door B, the bail 21 may be forced outwardly from between the jaws 14 and 15. The side 10 of the casing is provided with a slot 24 which extends from the forward edge of the side 10 rearwardly, 50 and which is of sufficient width to freely receive the bail 21 therethrough when the latter is inserted into the jaws 14 and 15. The jaws 14 and 15 are of a width slightly less than that of the bottom and top 11 and 55 12 of the casing so that the adjacent side portion of the bail 21 may enter the jaw member between the door casing A and the jaws. As the jaws 14 and 15 both bear against the side 10, the jaws are held in 60 true alinement at all times, and the movable jaw 15 is held flat against the inner face of the side 10 so that it can not move out of alinement with the fixed jaw 14.

The above described structure of catch 65 provides a device having relatively few

movable parts, the spring and jaw 15 being the only parts which move, and thus the device is relatively strong and durable and not easily distorted or damaged. The jaws 14 and 15 may be formed from metallic bars, or the like, and the casing from sheet metal, which is bent to the desired form, and stamped to provide the spring supporting finger 20. The co-acting member is formed of a single length of wire 70 which is bent in a manner which is easy to manufacture, and may be applied to the door and adjusted thereon without mortising or otherwise mutilating the door.

It is, of course, understood that various 75 changes may be made in the construction and design of this door catch, without departing from the spirit of this invention, and being restricted only by the scope of the following claims.

I claim:—

1. In a door catch, the combination, of a supporting casing, a fixed jaw secured to said casing, a movable jaw pivoted at its innermost end to the support above the fixed jaw, said jaws having opposed notches in their facing sides and beveled faces at their outer ends, means for guiding the free end of the movable jaw in its movement toward and from the fixed jaw, spring means between the support and the free end of the movable jaw for urging it toward the fixed jaw, and a co-acting member adapted to project between the beveled faces of said jaws and into said notches. 90

2. In a door catch, the combination, of a supporting casing, a fixed jaw secured to said casing, a movable jaw pivoted at its innermost end to the support above the fixed jaw, said jaws having opposed notches in 95 their facing sides and beveled faces at their outer ends, means for guiding the free end of the movable jaw in its movements toward and from the fixed jaw, spring means between the support and free end of the movable jaw for urging it toward the fixed jaw, and a co-acting member formed of a single length of wire bent to provide a bail 105 adapted for engagement at its crossed portion between said jaws and in said notches, 110 said member bent to form attaching portions extending at right angles from each end of the bail and having loops formed thereon and extending in opposite directions from the plane of the bail, said loops 115 adapted for securement against the inner side of a door to provide vertically extending slots in the co-acting member to permit adjustment thereof upon a door. 120

3. In a door catch, the combination of a 125 casing open and flanged at one side with the flanges adapted to be secured against a door casing and having a downturned finger in its top at the forward end of the casing and a recess in its side wall below 130

the finger, a fixed jaw secured in the bottom of the casing against the side thereof and having a notch in register with the recess, a movable jaw pivoted at its rear end 5 to the side of the casing and extending beneath said finger and having a notch adapted to register with the notch in the fixed jaw

and with the recess, a spring carried by the finger and bearing against the movable jaw for urging the same against the fixed jaw, 10 and a co-acting member adapted to project into the recess of the casing and into the notches of the jaws.

JOSEPH J. LYNN.
